CONTROLS FOR REFRIGERATION APPARATUS
Howard E. Caswell, East Syracuse, and James W. Endress, Syracuse, N.Y., assignors to Carrier Corporation, Syracuse, N.Y., a corporation of Delaware

Filed May 6, 1959, Ser. No. 811,463
4 Claims. (Cl. 62—115)

This invention relates broadly to air conditioning apparatus. More particularly this invention relates to a refrigeration machine utilized in air conditioning apparatus. Still more particularly this invention relates to a control employed on a refrigeration machine of the type under consideration.

In air conditioning equipment of the type to which this invention pertains there is included a refrigeration machine employed to cool a medium which is delivered to an enclosure to be supplied with conditioned air. Very often the medium to be supplied to the enclosure is water which has its temperature increased as it flows through a closed circuit including individual units spaced throughout the enclosure. Located in heat transfer relation with a coil in the circuit is the evaporator of the refrigeration machine, for the purpose of absorbing the heat and reducing the temperature of the water.

The refrigeration machine employed in the system described includes the usual components such as a compressor, condenser, economizer and evaporator connected to form a circuit for the flow of refrigerant in the conventional manner. In the case where the compressor in the machine described is of the centrifugal type, and includes a hermetic motor for driving the compressor, it has been found practical to utilize gaseous refrigerant from the economizer for the purpose of cooling the motor driving the compressor. As is well known, the economizer which in its broadest aspects may be described as reducing the pressure of the refrigerant flowing from the condenser to the evaporator in two stages, preparatory to its supply to the evaporator, has generated therein a supply of gaseous refrigerant through the commonly known "flashing off" process. In other words, when the refrigerant is reduced in pressure from the existing condenser pressure, a portion of the liquid refrigerant vaporizes, chilling the remaining liquid refrigerant and flowing either to the motor casing or directly to the compressor, depending on the manner in which the motor driving the compressor is cooled.

Under certain operating conditions of the air conditioning apparatus, as for illustration, during periods when the temperature of the ambient may fluctuate through a given twenty-four hour period, the normal pressure differences maintained in the refrigeration system under operation are drastically changed. For example, during the spring or fall season the ambient temperature which determines the temperature of the condensing medium used in the condenser may drop during the evening or night hours. The enclosure being served by the air conditioning system may still have a requirement for cooling, due to the presence of an excessive number of persons within the enclosure or due to an excessive load such as lights or heat generating equipment or machinery. Under these circumstances, the pressure within the low side of the system which includes the evaporator rises to a substantial level, while the pressure within the condenser is reduced substantially by virtue of the reduction in temperature of the condensing medium. In some extreme cases the temperature in the evaporator may even exceed that in the condenser, to the extent that a tendency for liquid refrigerant to reverse its flow in the machine occurs. Thus, liquid refrigerant tends to flow backward through the machine from the evaporator to the economizer and/or condenser. If the refrigeration machine being employed

2

in the air conditioning system utilizes a hermetic motor which is cooled by economizer gas, there is a tendency for the liquid refrigerant in the economizer to flow through the path normally provided for the flow of gaseous refrigerant from the economizer to the motor casing, so that a strong possibility that liquid refrigerant will enter the motor casing exists. Liquid refrigerant within the motor casing may be harmful to the windings of the motor and further, at start-up, may, by virtue of a relatively low pressure existing in the motor casing, vaporize and carry with it portions of the lubricant maintained in the motor casing. This can occur to such an extent that the control normally provided for terminating operation of the machine, due to low lubrication pressure, will interrupt operation of the machine to the discomfort of the occupants of the enclosure.

A related problem exists in equipment of the kind described wherein other means may be employed for cooling the motor and in equipment where it is not necessary to employ motor-cooling arrangements. In these instances the line for conducting gaseous refrigerant from the economizer connects directly to the compressor. A reverse flow of refrigerant in these machines may cause liquid refrigerant to be deposited in the compressor increasing the power requirement of the machine at the time the machine is operated initially.

The chief object of the invention is the provision of a control for a refrigeration machine of the kind under consideration which is operative to prevent flow of refrigerant within the machine in a direction opposite the direction for which the flow is designed.

A further object of the invention is the provision of a refrigeration machine control of the type described that is operative to vent the evaporator to a part of the refrigeration system which may, temporarily, have a pressure below that of the evaporator, although under normal design conditions that part would have a pressure in excess of the pressure in the evaporator.

Another object of this invention is the provision of a control for use in a refrigeration machine which is operative to sense abnormal pressure conditions within the evaporator and to vent the evaporator to the economizer so that either substantial equalization of pressure between the two elements of the machine occurs or the pressure in the economizer is supplemented so that the tendency of the liquid refrigerant in this system to flow from the evaporator is minimized.

Another object of the invention is a method of operating a refrigeration machine so that the tendency of liquid refrigerant to reverse its flow in the machine under circumstances where abnormal pressure relationships are encountered is minimized.

This invention in attaining the objects set forth contemplates a refrigeration system including a compressor, a condenser, an economizer and an evaporator connected to form a closed circuit, and means operable in response to a predetermined pressure relationship within the system for preventing reverse flow of refrigerant from the evaporator to the economizer by venting the zone of greater pressure to a zone of lower pressure.

Other objects and features of the invention will be apparent upon a consideration of the ensuing specification and drawings wherein:

FIGURE 1 is a diagrammatic representation of a refrigeration machine in an air conditioning system wherein the machine is equipped with a control of the type forming the subject of this invention;

FIGURE 2 is a partial perspective view of a portion of the evaporator and economizer of the refrigeration system shown in FIGURE 1 wherein certain parts are broken away in the interest of clarity.

FIGURE 3 is a view partly in elevation and partly in

section illustrating the control valve used in the invention.

FIGURE 4 is a diagrammatic view of a refrigeration machine equipped with a modified form of a control arrangement illustrating the invention.

For the purpose of illustrating the invention, an air conditioning system is diagrammatically illustrated in FIGURE 1. The system includes a refrigeration machine including a motor compressor unit 10 comprising a centrifugal compressor 11 and a hermetic motor 12 arranged to drive the compressor. Gaseous refrigerant in the refrigeration system is compressed by the compressor 11 and forwarded through discharge line 13 to a condenser 14 where it is liquefied as it passes in heat transfer relation with a condensing medium such as water flowing in a closed circuit including coil 29, pump 20 and cooling tower 28, together with appropriate piping.

The liquefied refrigerant flows through line 15 to the economizer 16 where it is subjected to a reduction in pressure causing portions of the liquid refrigerant to flash off or vaporize and cool the remaining body of liquid refrigerant. The cooled liquid refrigerant then flows from line 17 to the evaporator 18 which has assembled therein a coil 30 forming a part of a chilled water circuit, to be later described. As heat is extracted from the water in the coil 30 the liquid refrigerant is vaporized and flows through suction line 19 to the compressor to complete the refrigerant circuit.

As indicated above, a chilled water circuit includes coil 30 together with piping and a variable load represented at 40 which may be a unit comprising a coil for the flow of the chilled water and a fan for the purpose of providing a supply of room air over the coil to reduce the temperature of the room air for eventual recirculation to the room. In extracting heat from the room air the water leaving the unit 40 has its temperature increased. The water is then delivered by the pump 41 to the coil 30 for the purpose of reducing its temperature. The apparatus described is conventional and has enjoyed widespread use in air conditioning system for a substantial period of time.

Referring to the economizer construction, it will be observed that the economizer 16 is divided into an upper and lower chamber 25 and 26. A float valve controlled passage permits liquid refrigerant to flow from the upper chamber to the lower chamber. The upper chamber is maintained at substantially high side or condenser pressure while the lower chamber 26 is at a pressure intermediate high side and low side pressure. As the liquid flows into the chamber 26 portions thereof will vaporize and the vapor so created is utilized to cool the motor 12 by providing a path for its flow through line 30' from the economizer chamber to the motor casing. After the economizer gas flows in heat transfer with the motor, it is delivered to the compressor at an intermediate stage of compression through line 31 having a damper 33 responsive to a difference in pressure between the evaporator and the economizer. The purpose of this valve is to maintain a sufficient pressure within the motor chamber. This particular control forms the subject of the United States patent application Serial No. 620,129, filed November 2, 1956, now issued as United States Letters Patent 2,921,446, and assigned to the assignee of this invention.

As pointed out above, there are circumstances during which time the water flowing in the condenser cooling water circuit may encounter a substantial reduction in temperature, which, in turn, causes a sharp reduction in the condensing pressure. At the same time, the load imposed upon the evaporator by virtue of excessive loading of the unit 40 may be substantially high so that the temperature and pressure in the evaporator is increased to a degree where the evaporator pressure either equals or exceeds the condenser pressure. Under these circumstances, of course, there is a tendency for the liquid refrigerant which has collected in the economizer to flow in a direction opposite its normal intended direction. Unless such

a tendency is overcome, liquid refrigerant could flow in the line 30' into the motor casing and cause the harmful effects described above. To overcome the tendency of flow in this direction, applicant provides in the side of his cooler a movable flap member 50 which is weighted and designed so as to open in the manner of a check valve in response to a predetermined relation between the economizer and evaporator pressure. In other words, once the evaporator pressure exceeds the economizer pressure the member 50 will open causing the pressure in the evaporator to be reduced and the pressure in the economizer to increase. Thus, the tendency for the liquid refrigerant to flow from the evaporator to the economizer is overcome.

The member 50 illustrated in detail in FIGURE 3 includes mounting plate 60 having an opening 61 welded to a portion of the cooler, a flexible member 62 formed of neoprene secured to the mounting plate 60, a clamping plate 63 and a support plate 64. The latter two are connected to the flexible member 62 to provide rigidity to the assembly. The parts are designed so as to swing pivotally about fastening elements 65 in response to a predetermined difference in pressure between the gas on the opposite sides of the member 50.

In FIGURE 4 there is illustrated a second embodiment of the invention. The refrigeration machine illustrated in FIGURE 4 is substantially identical to the machine illustrated in FIGURE 1. Reference numerals indicating certain parts in FIGURE 1 are used to identify the corresponding parts shown in FIGURE 4. In the embodiment illustrated in FIGURE 4, line 57 connects the evaporator directly with the condenser. Flow of refrigerant through line 57 is under the control of a valve member structurally and functionally similar to that illustrated at 50 in FIGURE 1. In the operation of the embodiment illustrated in FIGURE 4, a pressure in the evaporator which is in excess of the pressure in the condenser causes refrigerant to flow through line 57 thus building up pressure in the condenser while reducing the pressure in the evaporator. Once a more normal pressure relationship between condenser and evaporator is obtained the tendency for refrigerant flow from the evaporator 18 to the economizer 16 is overcome and flow of refrigerant from the condenser to the evaporator is assured.

As indicated above this invention is operative under circumstances where unusual pressure conditions exist within the refrigeration system. The unusual pressure relationships are brought about by temperature differences in the media supplied to the condenser and evaporator for the purpose of liquefying and vaporizing respectively, the refrigerant. To fully accomplish the efficiencies available with the control schemes presented the pumps 20 and 41 should be energized to cause flow within their respective circuits prior to initiation of the compressor. Thus, flow of refrigerant between the condenser and evaporator, via lines 15, 17, economizer 16 and line 51 will occur and a refrigerating effect achieved.

While we have described a preferred embodiment of our invention, it will be understood our invention is not limited thereto, since it may be otherwise embodied within the scope of the following claims.

We claim:

1. Refrigeration apparatus comprising a compressor, a condenser, an economizer, an evaporator a line connecting the economizer and the evaporator to pass liquid refrigerant to said evaporator, means providing an additional passage between the evaporator and economizer and means normally closing said passage, said last-mentioned means being operative in response to a predetermined difference in pressure between the economizer and the evaporator to open said passage to reduce the pressure in the evaporator and increase the pressure in the economizer.

2. The invention set forth in claim 1 including a motor including a casing operating said compressor, a line connecting the economizer and the casing providing a path

for the flow of gaseous refrigerant formed in the economizer to the casing to cool the motor.

3. The invention set forth in claim 2 including a line connecting the casing and the compressor providing a path of flow for gaseous refrigerant flowing through the motor casing.

4. The method of operating a refrigeration machine including a compressor, a condenser, an economizer and a cooler connected to form a circuit for the flow of refrigerant, which consists in the steps of supplying gaseous refrigerant to the condenser for liquefaction therein, forwarding the refrigerant to the economizer wherein portions of the liquid refrigerant vaporize and cool the remaining liquid refrigerant, delivering the cooled liquid refrigerant to the evaporator for conversion to the gaseous state and reducing the evaporator pressure by automatically venting the evaporator to the economizer in response to a predetermined pressure relationship between the evaporator and the economizer.

ous state and reducing the evaporator pressure by automatically venting the evaporator to the economizer in response to a predetermined pressure relationship between the evaporator and the economizer.
